HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

PRINTING, FOLDING, AND DELIVERY MECHANISM.

Application filed June 11, 1927. Serial No. 198,109.

Machines designed especially for printing, folding and delivering loosely woven or light fabrics such as burlap or cotton often "choke up" in the printing mechanism or the folding mechanism because of the tendency of the material to wrinkle. This, as well as other contingencies which arise, frequently requires the machine to be stopped and the printing and folding mechanisms to be disconnected so that each mechanism may be moved independently of the other. Therefore, some means must be employed whereby the printing and folding mechanisms may be disconnected and reconnected only when in their proper relation to each other.

The object of this invention is to provide novel means whereby the machine may be stopped at any point in its cycle and the printing and folding mechanisms disconnected from each other, said means requiring the bringing of the printing and folding mechanisms back into their proper relation before the two mechanisms can be reconnected.

This invention more particularly includes a structure in which a clutch is provided in the driving connection between the two mechanisms, which clutch is operated by a lever for disconnecting and reconnecting the two mechanisms, lever controlling members also being provided, which members are frictionally mounted on a cylinder shaft of the printing mechanism and a cylinder shaft of the folding mechanism, said members being manually rotatable into position to permit the clutch operating lever to be manipulated to disconnect the two mechanisms while they are still in their proper relation to each other and requiring the two mechanisms to be brought back into their proper relation before the clutch operating lever can be operated to reconnect the mechanisms.

A practical embodiment of my invention is represented in the accompanying drawings, in which

Fig. 1 represents a diagrammatic side view of the connected printing and folding mechanisms.

Fig. 2 represents an enlarged detail side view showing the parts in full lines in the positions they assume when the hand wheels have been moved into position to permit the operating lever to be moved to disconnect the two mechanisms; and in dotted lines in the positions the parts assume when the op-

erating lever has been moved to disconnect the two mechanisms.

Fig. 3 represents a detail plan view of the same.

The printing mechanism is herein shown as comprising the first and second printing couples 1, 2 and 3, 4. The folding and delivery mechanism is herein shown as comprising the folding cylinders 5, 6, the delivery cylinder 7 and the endless delivery carrier 8. The driving connection between the printing mechanism and the folding and delivery mechanism is shown as comprising a shaft 9 connected at one end to the impression cylinder 2 of the first printing couple through the clutch 10, 11 and train of gears 12, 13, 14, 15 and at its other end to the folding and delivery mechanism through a train of gears 16, 17, 18, 19. The coacting rotary cutters for severing the sheets from the webs are represented by 20, 21.

The member 11 of the clutch which carries the gear 12 is loosely mounted on the shaft 9 and the member 10 of the clutch is slidably keyed on said shaft. This clutch is utilized for disconnecting and reconnecting the printing mechanism from and to the delivery mechanism. The four armed clutch operating lever is pivoted at 22, one arm 23 being connected to the movable clutch member 10, another arm 24 being utilized as a handle, the third arm 25 being connected to one end of a rod 26, and the fourth arm 27 being connected to one end of a rod 28. The other ends of the rods 26, 28 are bifurcated to slidably embrace their respective cylinder shafts 29, 30 of the printing and folding mechanisms.

Hand wheels 31 and 32 are frictionally mounted upon their respective shafts 29 and 30 so that the hand wheels may be manually rotated on said shafts. These hand wheels are respectively provided with circular flanges 33 and 34 having openings 35 and 36 therethrough. The rods 26 and 28 of the clutch operating lever are provided with studs 37 and 38 which are located within their respective hand wheel flanges 33 and 34 when the clutch is closed and the printing and folding mechanisms are operatively connected, so that the lever cannot be operated until both of the hand wheels are rotatively adjusted to bring the openings 35 and 36 in their circular flanges 33 and 34

opposite the studs 37 and 38. A suitable keeper 39 engages the handle arm 24 of the clutch operating lever to hold the lever in its different positions.

5 In operation: When a "choke" or other contingency arises, the machine is stopped. The hand wheels 31 and 32 are then turned on their respective cylinder shafts 29 and 30 until the openings 35 and 36 in the circular flanges 33 and 34 are brought opposite to the studs 37 and 38 on the rods 26 and 28. This will permit the clutch operating lever to be manipulated to withdraw the studs 37 and 38 from within their flanges and to 10 withdraw the clutch member 10 from its engagement with the clutch member 11, thereby disconnecting the printing mechanism from the folding mechanism. The printing mechanism or the folding mechanism may 15 then be moved independently of the other to remove the "choke," or for any other purpose. The two mechanisms are then returned to their original position in proper relation to each other by bringing the openings 35 and 36 in the flanges 33 and 34 of 20 the hand wheels 31 and 32 opposite the studs 37 and 38 on the rods 26 and 28 of the clutch operating lever. The clutch operating lever can then be moved to insert the 25 studs within their circular flanges and to bring the clutch member 10 into engagement with the clutch member 11 to reconnect the mechanisms. The machine may then be started.

30 35 From the above description it will be seen that I have provided means whereby the printing mechanism may be stopped at any point in its cycle and disconnected from the folding mechanism, said means requiring 40 the printing mechanism and the folding mechanisms to be brought back into their proper relation before they can be reconnected.

45 The "throw-out" means herein described is not only useful for the ready elimination of "chokes" in the printing mechanism or the folding mechanism but is also useful for permitting the printing mechanism to be disconnected from the folding mechanism 50 while "making-ready" and for mounting the plates, or for any other purpose.

55 While I have referred particularly to the application of this invention to machines for printing and folding loosely woven or light fabrics, it is to be understood that this invention is well adapted for use in machines for printing and folding in general.

60 It is evident that various changes may be resorted to in the construction, form and arrangement of the several parts without departing from the spirit and scope of my invention; hence, I do not intend to be limited to the particular embodiment herein 65 shown and described, but

What I claim is:—

1. A printing mechanism, a folding mechanism, their driving connection, and means manually movable to permit the disconnection and reconnection of said mechanisms only when in their proper relation to each other. 70

2. A printing mechanism, a folding mechanism, their driving connection, means for disconnecting and reconnecting said mechanisms, and members manually movable to permit the operation of said means only when the mechanisms are in their proper relation to each other. 75

3. A printing mechanism, a folding mechanism, their driving connection including a clutch, a clutch operating lever for disconnecting and reconnecting said mechanisms, and lever controlling members movable into position to permit the operation of said lever only when the mechanisms are in their proper relation to each other. 80

4. A printing mechanism, a folding mechanism, their driving connection including a clutch, said printing mechanism including a cylinder shaft, said folding mechanism including a cylinder shaft, a clutch operating lever for disconnecting and reconnecting said mechanisms, and lever controlling members frictionally mounted on said shafts and manually movable into position to permit the operation of said lever only when the mechanisms are in their proper relation to each other. 90

5. A printing mechanism, a folding mechanism, their driving connection including a clutch, said printing mechanism including a cylinder shaft, said folding mechanism including a cylinder shaft, a clutch operating lever for disconnecting and reconnecting said mechanisms, rods attached to said lever and slidably on said shafts, studs on said rods, and hand wheels frictionally mounted on said shafts and provided with annular flanges engaging said studs, said flanges having openings arranged to be brought into position to release said studs for permitting the operation of the lever only when the said mechanisms are in their proper relation to each other. 100

6. A printing mechanism, a folding and delivery mechanism, their driving connection, and means manually movable to permit the disconnection and reconnection of said mechanisms only when in their proper relation to each other. 110

7. A printing mechanism, a folding and delivery mechanism, their driving connection, means for disconnecting and reconnecting said mechanisms, and members manually movable to permit the operation of said means only when the mechanisms are in their proper relation to each other. 120

8. A printing mechanism, a folding and delivery mechanism, their driving connec- 125

tion including a clutch, a clutch operating lever for disconnecting, and reconnecting said mechanisms, and lever controlling members movable into position to permit the 5 operation of said lever only when the mechanisms are in their proper relation to each other.

9. A printing mechanism, a folding and delivery mechanism, their driving connection 10 including a clutch, said printing mechanism including a cylinder shaft, said folding and delivery mechanism including a cylinder shaft, a clutch operating lever for disconnecting and reconnecting said mechanisms, 15 and lever controlling members frictionally mounted on said shafts and manually movable into position to permit the operation of said lever only when the mechanisms are in their proper relation to each other.

20 10. A printing mechanism, a folding and

delivery mechanism, their driving connection including a clutch, said printing mechanism including a cylinder shaft, said folding and delivery mechanism including a cylinder shaft, a clutch operating lever for disconnecting and reconnecting said mechanisms, rods attached to said lever and slidable on said shafts, studs on said rods, and hand wheels frictionally mounted on said shafts and provided with annular flanges engaging said studs, said flanges having openings arranged to be brought into position to release said studs for permitting the operation of the lever only when the said mechanisms are in their proper relation to 25 each other.

In testimony, that I claim the foregoing as my invention, I have signed my name this 9th day of June, 1927.

HOWARD M. BARBER.
